[57] **CLAIM**

The ornamental design for a support stand for use in X-raying a human foot, as shown and described.

DESCRIPTION

FIG. 1 is a perspective view of a support stand for use in X-raying a human foot showing my new design; FIG. 2 is a side elevational view thereof, the opposite side view being a mirror image of the figure shown; FIG. 3 is an end elevational view thereof, the opposite end view being the same as the figure shown; FIG. 4 is a top plan view thereof; and, FIG. 5 is a bottom plan view thereof.

The claimed design invention is visually and radio-transparent except for the transverse horizontal visual and radio-opaque wire embedded near the after end of the foot supporting platform.

FIG. 1.

FIG. 2.

FIG. 3.

FIG. 4.

FIG. 5.
